No. 14,455

Nov 27, 1883

UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A CHILD'S COAT.

SPECIFICATION forming part of Design No. 14,455, dated November 27, 1883.

Application filed October 1, 1883. Term of patent 3½ years.

To all whom it may concern:

Be it known that I, MARY TURNER, of the city, county, and State of New York, have invented and produced a new and original Design for a Pattern of a Child's Coat, (numbered 8,889;) and I do hereby declare that the engraved prints accompanying this specification convey to any one accustomed to using paper patterns a clear understanding of how a garment made up by the pattern will appear.

The design shows narrow sack-fronts single-breasted for a short distance at the top and double-breasted for the remainder of their length, a half-fitted back exhibiting an under 15 box-plait at the lower end of its center seam

and side plaits at the lower parts of the side seams, and a belt that passes through straps fastened over the seams, and displays a buckle at the left side of the closing. A deep shawl-collar and coat-sleeves are added.

What I claim as my invention, and desire to secure by Letters Patent, is—

The design for a child's coat, as shown in the engraved prints accompanying this specification.

MARY TURNER.

Witnesses:

ALFRED FRANCIS,
MARCELLUS CARLETON SHATTUCK.
